UNITED STATES PATENT OFFICE

JOHN ROBERT SPOOR, OF KALAMAZOO, MICHIGAN

STOCK-CONTROLLING MEANS FOR PAPER-MAKING MACHINES

Application filed November 28, 1928. Serial No. 322,350.

The objects of this invention are:

First, to provide a regulator that affords a simple and effective means of controlling the consistency of the paper stock that is delivered to the stuff chest of a paper making machine.

Second, to provide improved means for controlling the regulator for maintaining the weight of the paper stock.

10 This invention is a development and improvement of the structure of my Patent No. 1,689,755, Oct. 30, 1928.

Objects pertaining to details and economies of operation and construction will definitely 15 appear from the description to follow.

A machine embodying the features of my invention is illustrated in the accompanying drawing, in which:

Fig. 1 is a diagrammatic elevation view of 20 my complete paper stock regulator means.

Fig. 2 is a side elevation of my improved regulator for controlling the consistency of wet paper stock, dotted lines indicating the gate and the overflow partition part of the 25 hopper being broken away to more clearly illustrate the restricted discharge.

Fig. 3 is a top plan view of the regulating stuff chest showing mainly the gate in a central position for controlling the overflow to 30 the discharge.

Fig. 4 is a vertical section taken on line 3—3 of Fig. 1 showing mainly the spiral conveyor for retarding the flow of stock, the inlet pipe thereto showing a lateral discharge 35 to prevent the splashing of the paper stock.

Fig. 5 is a detail sectional plan view taken on line 5—5 of Fig. 2.

The parts will be identified by their numerals of reference which are the same in all 40 the views.

1 is a Jordan beater of the usual construction. 2 is the supply chest for the Jordan beater. 21 is the stock pipe delivering into the supply chest 2. 3 is the delivery pipe 45 from the Jordan beater. 4 is the regulating stuff chest to which pipe 3 delivers.

The regulating stuff chest 4 is provided with a dam partition 41 forming a supply of compartment 42 which overflows the dam 50 partition 41. A gate 43 is provided on the

top of partition 41. 44 is the overflow compartment with the overflow pipe 45 delivering from the bottom thereof. 46 is the regulating compartment with a hopper 47 at the top delivering outwardly through pipe 48 to 55 the controlling hopper.

5 is the balanced controlling hopper. 6 is the delivery hopper. 7 is the pipe from the delivery hopper to the paper machine. 8 is the stuff chest of a paper making machine 60 receiving stock through pipe 7. The balanced hopper 5 is supported from the bracket 9 beneath the regulating stuff chest 4.

10 is the bifurcated balanced lever fulcrumed at 101 on the hanger bracket 9 beneath the chest 4. The bifurcations engage trunnions 51 on the said balanced hopper 5 which is balanced by the counterweight 102 on said lever 10.

The stock is thinned by supplying water 70 to the Jordan beater through the inlet pipe 12 which is controlled by needle valve 13 by the variations of weight in the balanced controlling hopper 5. The needle valve 13 is controlled by lever 11 which is supported by arm 111 secured to the chest 4. 112 is the fulcrum for the lever 11 which is bifurcated at 113 and engages the valve stem 131 for opening and closing the needle valve.

The lever 11 is actuated by a pin 114 on the 80 lever 10. The arm 111 yields enough to permit the necessary actuation of the valve stem by engagement with the bifurcated end of the lever 11.

The balanced controlling hopper 5 is supplied from the pipe 48 and is provided with a spiral passage formed by a blade 52 very similar to the vane of a spiral conveyor which retards the flow of the stock therethrough 85 keeping it of even consistency and retaining it by friction so that it is maintained substantially full. If the stock thickens it does not flow so readily and at once accumulates, overbalancing the counterweight, throwing the end of lever 11 up and opening the needle valve 13 and at once admitting an extra supply of water through pipe 12 to the supply chest 2 of the Jordan.

53 is the central vent pipe in the balanced 90 hopper 5 and insures the venting and escape 100

of air from the contained stock. This hopper has its bottom somewhat contracted at 54 with a discharge elbow 55 to deliver the stock from the hopper laterally so it will be admixed with the contents of hopper 6. The elbow 54 is directed to deliver the stream of stock along with the stock from the overflow pipe 45.

From this description it will be observed 10 that if the paper stock becomes unduly heavy it will, through the balanced controlling hopper, be accumulated, owing to the spiral passage, offering resistance so that the counterweight 102 will be overbalanced and the 13 counterweight lever 10 will, through pin 114 react on the lever 11 and at once open the needle valve 13, which will permit water to enter the supply chest for the Jordan beater and at once thin the stock that is being delivered from the Jordan.

This action is very gradual as it should be because the stock is delivered in as near the right consistency as possible and the addition of a comparatively small stream corrects the 25 same and delivers a very even stock to the paper machine which insures the manufacture of a sheet of substantially even weight, a thing which results in the production of the maximum sheet area of the weight from the 30 paper stock as required.

It will be seen that the present structure is an improvement and advance over the structure of my said patent in providing an effective means for retaining and supporting 35 the stock in the counterbalanced controlling hopper. The thing is capable of complete regulation.

The adjustment of the gate 43 insures a substantially correct flow of the stock to the 40 counterbalance device permitting the rest to overflow through pipe 45. The regulation is instantaneous, the slightest variation in weight at once admitting a small amount of water and increasing the same if the stock 45 is not at once thinned to the required amount.

The structure is exceedingly sensitive. The maintenance of the even weight of the sheet is very remarkable, there being no perceptible variation in the succeeding lengths of 50 paper when the stock is delivered within a reasonable range of requirements to the supply chest for the Jordan. The structure is very compact. There is little or nothing to get out of order.

Having thus described my invention, what 55 I claim as new and desire to secure by Letters Patent, is:

1. In a stock controlling means for paper making machines, the combination with a 60 Jordan beater and stuff supply box therefor of a regulating supply chest with a dam partition thereacross with gate to regulate the overflow, an overflow pipe and a discharge pipe therefrom, a balanced hopper with spiral passage therethrough for the said paper

stock from the discharge pipe, a bifurcated counterbalance lever carrying the said hopper, a water supply pipe to the stuff supply box of the said Jordan, a needle valve for controlling the same, a lever for operating 70 said needle valve with connection to the counterbalance lever of the hopper, coacting as specified.

2. In a stock controlling means for paper making machines, the combination of a regulating supply chest with discharge and overflow, a balanced hopper with spiral passage therethrough to receive the paper stock from the discharge, counterbalance means for supporting the same, a water supply pipe with 80 control valve, connections from the counterbalance lever to said valve for admitting water to thin the stock, as specified.

In witness whereof I have hereunto set my hand.

JOHN ROBERT SPOOR.
